(57) **CLAIM**

The ornamental design for a toy excavator, as shown and described.

DESCRIPTION

FIG. 1 is a first perspective view of a toy excavator in an unfolded configuration showing my new design;
FIG. 2 is a second perspective view thereof;
FIG. 3 is a front view thereof;
FIG. 4 is a back view thereof;
FIG. 5 is a left side view thereof;
FIG. 6 is a right side view thereof;
FIG. 7 is a top view thereof;
FIG. 8 is a bottom view thereof; and,
FIG. 9 is a perspective view of the toy excavator thereof in a folded configuration.

The broken lines and the areas within them in the drawings depict portions of the toy excavator that form no part of the claimed design.
